Brake-Beam.

No. 870,186.

Specification of Letters Patent.

Patented Nov. 5, 1907.

Application filed May 6, 1907. Serial No. 371,990.

To all whom it may concern:

Be it known that I, CHARLES A. LINDSTRÖM, of Allegheny, Allegheny county, Pennsylvania, have invented a new and useful Improvement in Brake-
5 Beams, of which the following is a full, clear, and exact description, reference being had to the accompanying drawings, forming part of this specification, in which—

Figure 1 is a plan view partly broken away of a brake beam embodying my invention; Fig. 2 is an edge or
10 front view of the same with the tension member partially broken away; Fig. 3 is a similar view of one end of the compression member with the brake shoe support removed; Figs. 4 and 5 are sections taken on the lines IV—IV and V—V respectively of Fig. 2; and
15 Fig. 6 is a section on the line VI—VI of Fig. 3.

My invention has relation to that class of brake beams generally designated as trussed beams, and is intended to provide a brake beam having its compression member so designed and constructed as to obtain
20 a maximum of strength with a minimum amount of metal. In a brake beam of this character, in order that the compression member may have sufficient strength both horizontally and vertically, it should be proportioned according to the requirements of a
25 column of two different lengths or units; that is, horizontally in the direction of the applied force, which should have proportions required by a column whose length is the distance from the center of the beam, where it is supported by center strut, to the end of the
30 beam, where it is held by the tension member or rod. Vertically, the compression member should have proportions such as are required by a column whose length is the distance between the two ends, and which is twice the length first mentioned. The weakest part
35 of the column is at the center of its length, at which point the effective area of the material should be the greatest. The further a given area of the material is removed from the neutral axis of the section, the greater is the efficiency to withstand bending force. It has

40 been found that a compression member constructed from a single rolled piece of material will not meet these requirements with a minimum amount of metal, by reason of the fact that such a member has the same area throughout its length, and if made sufficiently
45 heavy at its central portion, there is more material at the end portions than the stresses demand. It has also been difficult to meet these requirements by a built-up compression member owing to the fact that the members or parts thereof cannot easily be so shaped and
50 connected as to give the desired disposition of metal.

It is well known that in built-up trussed constructions, such as brake beams or bolsters, a camber or arching of the compression member in a direction away from the applied force gives the strongest construction; and this arching is easily done when the

member is cast, as extra operations are avoided, which are necessary with other material. Further, cast material is more suitable to compression stresses than to tensile stresses, and forged or rolled material more suitable to tensile stresses.

60

My present invention is therefore designed to meet objections made against similar structures heretofore; to use in each member the kind of material most suitable to the stresses to which they are subjected, and to construct the compression member in a shape so as
65 to be most effective with the minimum amount of material.

Referring to the accompanying drawings, the numeral 2 designates the compression member which is formed by an integral casting of trough shape in cross-section, its open side being in the direction of the brake shoes. The free edges of its flanges are reinforced, preferably exteriorly by means of the longitudinal ribs or projections 3 which extend continuously from one end of the member to the other. The section is
70 further reinforced in a vertical direction by means of a plurality of transverse ribs or projections 4 which connect the flanges of the section at intervals and divide the trough into a series of cell like compartments. These ribs to facilitate removal of the pattern from
75 the sand and to avoid cores, are made parallel with each other instead of at right angles to the camber of the compression member. The central portion of the web 5 is preferably cored out at intervals, as indicated at 6 to form openings which reduce the weight
80 of the member, this metal being removed along the central line where it has little effect upon the strength of the member. The web, however, is preferably reinforced along each side of this series of openings, by
85 the longitudinally extending ribs 7 which unite the transverse ribs 4. The reinforcing ribs 3, 4 and 7 will prevent buckling of the free edges of the compression member, and less average thickness of the walls may be used.

The compression member has its greatest width at
90 its central portion, and decreases in width toward each end, as shown in Fig. 2. It is also preferably arched between its ends in a longitudinal direction. The ends of the member are of reduced thickness in a vertical direction, as shown at 8 in Fig. 3 to receive the brake
95 shoe heads or supports 9 which embrace the reduced end portions and are secured by the bolts or rivets 9^a which extend through the bearing portions 9^b.

10 designates the usual tension member which is preferably a continuous bent rod whose end portions extend up through the end portions of the compression member, and are secured by the nuts 11 which bear against seats 12 formed integral with the heads or supports 9.

13 is the usual center strut which is secured between
110

the flanges of the compression member. This strut carries the bearings for the central portion of the tension member 10.

By the construction above described I provide a 5 brake beam whose compression member can be cheaply and readily manufactured; and which is of a character to give a maximum moment of resistance to compression strains, with the use of a minimum amount of metal, and which also fulfils the other requirements 10 hereinbefore stated.

A mechanic skilled in this art may make various changes in the details of construction, without departing from the spirit and scope of my invention, since.

What I claim is:—

15. 1. A brake beam having a compression member formed by an integral casting having a greater effective area of material at its central portion than at its ends; substantially as described.
2. A trussed brake beam having its compression member formed by an integral casting of trough shape in cross-section, and of greater effective sectional area at its central portion than at its ends; substantially as described.
20. 3. A trussed brake beam having its compression member formed by an integral casting of trough shape in cross-section, and having reinforcing ribs; substantially as described.
25. 4. A brake beam having a compression member formed by a single casting of trough shape in cross-section, the free edges of the flanges of the section having longitudinally extending ribs or enlargements; substantially as described.
30. 5. A brake beam having a compression member formed by an integral casting of trough shape in cross-section,

and having the flanges of the section connected by transverse ribs; substantially as described.

6. In a brake beam, a compression member consisting of 35 an integral casting of trough shape in cross-section, and having its vertical or web portion provided with longitudinally-extending ribs; substantially as described.

7. In a brake beam, a compression member consisting of 40 an integral casting having openings along the center line of its vertical or web portion, and longitudinally-extending reinforcing ribs adjacent to said openings; substantially as described.

8. A trussed brake beam having a compression member formed by an integral casting of trough shape in cross-section, 45 said section being deeper at the central portion of the member than at its ends; substantially as described.

9. A trussed brake beam, having a compression member formed of an integral casting of trough shape in cross-section, and formed with longitudinally and transversely-extending reinforcements; substantially as described. 50

10. A brake beam having a compressed member formed by an integral casting of trough shape in cross-section, and arched between its ends in a horizontal direction; substantially as described. 55

11. A brake beam having a compression member formed by an integral casting of trough shape in cross-section, said cross-section being deeper at the central portion of the member than at its ends, and the member arched between its ends in a horizontal direction; substantially as described. 60

In testimony whereof, I have hereunto set my hand.

CHARLES A. LINDSTRÖM.
